(57) **CLAIM**

The ornamental design for a luminaire, substantially as shown and described.

DESCRIPTION

FIG. 1 is a front perspective view of a first embodiment of our luminaire.

FIG. 2 is a front side view of the luminaire of FIG. 1.

FIG. 3 is a back side view of the luminaire of FIG. 1.

FIG. 4 is a right end view of the luminaire of FIG. 1.

FIG. 5 is a left end view of the luminaire of FIG. 1.

FIG. 6 is a top view of the luminaire of FIG. 1.

FIG. 7 is a bottom view of the luminaire of FIG. 1.

FIG. 8 illustrates the profile of the lower surfaces of the luminaire of FIG. 1, as taken in any vertical plane perpendicular to the length of the luminaire.

FIG. 9 is a front perspective view of a second embodiment of our luminaire.

FIG. 10 is a front side view of the luminaire of FIG. 9.

FIG. 11 is a back side view of the luminaire of FIG. 9.

FIG. 12 is a right end view of the luminaire of FIG. 9.

FIG. 13 is a left end view of the luminaire of FIG. 9.

FIG. 14 is a top view of the luminaire of FIG. 9; and,

FIG. 15 is a bottom view of the luminaire of FIG. 9.

The broken (dash) lines illustrate environmental features that form no part of the claimed design and indicate, for example, how the claimed design might be extended to form a closed shape, such as a square. The broken (dot-dash) lines indicate boundaries of the claimed design and form no part of the claimed design. For example, a broken (dot-dash) transverse line beyond which all lines are dashed indicates that the design may be employed in products of different lengths.
